UNITED STATES PATENT OFFICE

92,578

DESIGN FOR A RADIOCABINET

John D. Brophy, New York, N. Y.

Application August 11, 1933, Serial No. 48,997

Term of patent 7 years

To all whom it may concern:

Be it known that I, JOHN D. BROPHY, a citizen of the United States, residing in the Borough of Manhattan, in the city, county and State of New York, have invented a new, original, and ornamental Design for Radio Cabinets, of which the following is a specification, reference being had to the accompanying drawing, forming part hereof.

In the drawing, the figure is a front elevation of the new design for radio cabinets.

As is indicated by the shading in the drawing, my ornamental radio cabinet is in the shape of a sphere and is composed of a lower hemi-spherical section mounted on a circular base member and an upper hemi-spherical section mounted upon the lower section.

I claim:

The ornamental design for a radio cabinet as shown and described.

JOHN D. BROPHY.
